JOURNAL BOX

Albert O. Buckius, Cleveland Heights, Ohio, and
 Thomas E. Newberry, Northumberland, Pa., as-
 signors to National Malleable and Steel Cast-
 ings Company, Cleveland, Ohio, a corporation
 of Ohio

Application April 30, 1936, Serial No. 77,076

8 Claims. (Cl. 308—86)

This invention relates to journal boxes for rail-
 way cars, particularly that type that have what
 are known as free oiling systems of lubrication.

One object of our invention is to provide means
 5 in a journal box to prevent the oil being thrown
 to rearward portions thereof by the oil conveying
 or throwing member, of the free oiling mecha-
 nism, into such areas that it could escape through
 the rear end of the box. This means may com-
 10 prise a removable baffle positioned between the
 oil conveying member and the inner end of the
 journal box.

Another object of our invention is the provision
 15 of means to limit movement of the journal box
 away from the journal after the parts have been
 assembled to prevent displacement of and dam-
 age to certain of the parts. This means is pref-
 erably combined or associated with the removable
 20 baffle. Other objects and advantages of our in-
 vention will be apparent from the following de-
 tailed description taken in conjunction with the
 drawings, in which:

Figure 1 is a vertical sectional view taken lon-
 gitudinally through a journal box embodying our
 25 invention.

Figure 2 is an end view of the journal box
 shown in Fig. 1 with the cover removed and the
 box partly broken away to show the interior.

Figure 3 is a horizontal sectional view taken
 30 on line 3—3 of Fig. 1, the journal being omitted.

Figure 4 is an enlarged sectional view of a de-
 tail of our invention taken on line 4—4 of Fig. 1.

Figure 5 is a detail view in front elevation of
 the baffle member.

Figure 6 is a partial sectional view taken on
 line 6—6 of Fig. 5, and

Figure 7 is a partial sectional view illustrating
 the method of assembly of the baffle.

Referring to the drawings, there is shown a
 40 journal 1 extending into the journal box 2. The
 journal box may be enlarged at its forward end,
 providing a deepened portion to form an oil res-
 ervoir 3. The usual brass 4 and wedge 5 are po-
 sitioned between the top of the journal, and the
 45 under surface 6 of the top of the journal box.
 Secured to the end of the journal, as by bolts 7,
 is a paddle member or dipper 8 arranged to ro-
 tate with the journal and convey oil to the top of
 the box. The dipper may be formed with dis-
 50 similar end portions 9 and 10 that are adapted
 to extend downwardly into the oil reservoir, and
 during the course of its rotation at low speeds to
 drop oil into a trough 11 in a projecting portion
 12 of the wedge. At high speeds the oil adhering
 55 to the dipper is thrown by centrifugal force onto

the upper wall 13 of the journal box and runs
 down into troughs 14, 14 and from there drops
 into the trough 11. The oil is then conveyed
 by the usual passages 15 in the brass to the bear-
 5 ing surfaces on the journal. The excess oil over
 that necessary to properly lubricate the journal
 drops to the bottom of the box and normally
 finds its way back into the oil reservoir 3. The
 usual dust guard 16 and obturating ring 17 may
 be used to prevent dust from entering and oil
 10 escaping from the box. The front end of the
 journal box may be closed by the cover 18 and
 made oil-tight by the use of gasket 19. Stud
 bolts 20 and nuts 21 are used to secure the cover
 15 to the box.

We have found that, if means are not provided
 to prevent it, the action of the dipper striking
 the oil is apt to deflect small particles thereof
 from the reservoir rearwardly in such a manner
 that it strikes the under side of the journal and
 20 is again deflected toward the rear of the box
 into such a position that it may escape through
 the bottom of the dust guard slot 22 or otherwise
 find its way out of the rear of the journal box.

Since this type of box is designed to run for
 comparatively long periods without the further
 addition of oil, it is obvious that even small
 quantities of oil escaping from time to time
 through the rear of the box will soon deplete the
 30 initial oil supply to a dangerously low point. In
 order to prevent this escape of oil, we provide a
 novel baffle member 23 comprising a substantially
 vertical portion 24, formed at its upper end with
 a substantially horizontal web 25, from which
 35 web extends another vertical portion 26. Ex-
 tending rearwardly from the web 26 is an axially
 projecting portion 27 which, as will be clearly
 seen from Figs. 1 and 5, is offset vertically from
 the web 25 for a purpose to be later described.
 40 The baffle may be reinforced along its side and
 bottom edges by a flange 28. The baffle member
 is positioned within the journal box behind pro-
 jections 29, 29 located on either side of the box.
 An upstanding web 30 in the bottom of the res-
 45ervoir may be provided in front of the baffle to
 hold the bottom thereof against forward move-
 ment. Extending rearwardly from the member
 23 are substantially horizontal supporting brack-
 50 etts 31 which are adapted to rest on the bottom
 wall 32 of the journal box. These brackets may
 be reinforced by vertically extending webs 33, 33.

In order to function according to one of the
 objects of this invention, as will be later more
 fully described, the baffle must be applied after
 the journal box has been assembled with its brass
 55

and wedge over the journal. Accordingly, we have provided novel means for maintaining the baffle in position without sacrificing ease of assembly and disassembly. For this purpose we use a flat member 34, preferably made of spring steel, extending across the front face of the baffle and into overlapping relation with the projections 29, 29. The spring member is drawn tight against the baffle and projections by means of a bolt 35 and a nut 36. Since access to that portion of the box rearwardly of the baffle is impossible when the latter is in position, we provide a recess 37 (see Figs. 4 and 6) adapted to receive the head of the bolt and prevent it from turning. Lugs 38, 38 are adapted to be bent over the head in the manner indicated in Fig. 4, after the latter has been assembled with the baffle to hold the bolt in position. These lugs may be originally formed, as illustrated by the dotted lines in Fig. 4, to permit insertion of the head of the bolt into the recess. The spring member 34 should be prevented from turning after it has been assembled as by means of lugs 39, 39 extending forwardly from the member 23.

In order to limit upward movement of the baffle, we provide lugs 40, 40 on the front side thereof which enter notched portions 41, 41 of the projections 29, 29. Openings 42, 42 are formed in the baffle member to permit return of the oil to the forward portion of the oil reservoir. It will be understood that the brass 4 and the wedge 5 are inserted after the journal box has been jacked up relative to the journal. Considerable damage may be done to the dipper if the box is thoughtlessly raised when the dipper is in vertical position, as shown in Figs. 1 and 2, due to the fact that heretofore means has not been provided to limit relative vertical movement between the journal box and the journal. It will be appreciated that without some means to limit upward movement thereof, the journal box may be raised to such an extent that the dipper will contact the lower wall of the box, causing the dipper to be bent out of shape. Furthermore, in assembling the trucks to which the journal boxes are applied and also under certain conditions encountered in service the journal brass and wedge may move out of their normal positions and cause a hot box if permitted to run without correcting the displacement. To obviate these difficulties, we have provided means on the baffle member 23 to definitely limit upward movement of the box and maintain the brass and wedge in operative position. It will be noted that the baffle is constructed with the vertical portion 26 offset rearwardly from the main portion 24. This offset will allow for sufficient axial movement of the journal relative to the box without the collar 43 of the journal contacting the portion 26 of the baffle. The portion 27 is spaced a small distance beneath the journal and obviously forms a stop which will limit upward movement of the box relative to the journal so long as the baffle is in operative position. The clearance between portion 27 and the journal is preferably small enough to insure maintenance of the proper relation between the brass and wedge. The upper surface 44 of the web 27 may be made concentric with the journal, as will be seen from Fig. 2.

In Fig. 5 we have illustrated the adaptability of the member 23 to different sizes of journals. In service, journals of various diameters may be encountered for a given capacity journal due to wear or because they have been turned down

to smooth up the bearing surface. In the event that an undersized journal is encountered, we provide a shim 45 riveted or otherwise secured to the web 27 and of such thickness that the clearance between the upper surface 46 of the shim and the under side of the journal may be the desired amount. In Fig. 5 the dot-dash line represents the normal diameter of the journal, whereas the solid line illustrates a journal having a diameter slightly smaller than normal. It will be noted that the clearance between the surface 44 and the dot-dash line is substantially the same as the clearance between surface 46 and the solid line. This, of course, is merely illustrative, and the clearance between the baffle member and the journal may be made any desired amount that will limit upward movement of the journal box to such an extent as will positively prevent damage to the dipper and retain the parts in place.

In assembling, the combined baffle and stop member is first entered in a substantially horizontal position, as shown by the solid lines in Fig. 7, so that its widest portion passes through the notches 41, 41 in the projections 29, 29. It is then rotated to a position as shown by the dot-dash line and further moved to a vertical position behind the projections 29, 29 and 30 and seated thereagainst. The spring member 34 and nut 35 are then applied to lock the baffle rigid with the box. It will be noted that the member 23 is cut away at the bottom at 47, 47 to form a portion of slightly less width than the distance between projections 29, 29; so that as further rotation is prevented by the upper portions of the extensions 29, 29, the lower part of the baffle may be moved to the rear of the lower extension 30 and then dropped behind the latter. This is necessary to assemble the member due to the small amount of space available between the bottom of the journal and the box. During the latter part of the rotating movement of the assembly operation the narrowed part of the baffle member need not pass through notches 41, 41 but may move between the projections 29, 29. However, the member can be used in journal boxes in which there is ample clearance for it to be inserted, even though it is of the same width throughout its vertical extent. To avoid damage to the journal and as a convenience in assembling, member 23 may be beveled as at 48 and 49 so as to provide sufficient clearance between these surfaces and the corner 50 and the like of the box.

It will be noted that the baffle member is positioned intermediate the ends of the enlarged portion 3 of the oil reservoir, thus dividing it into a pair of compartments. Any dirt entering the box through the dust guard will collect in the space between the rear side of the baffle and the rear wall of the portion 3 up to the level of the bottoms of openings 42. In this manner foreign matter is prevented from passing into the forward part of the reservoir where it could be carried by the dipper to the bearing surfaces.

While we have shown our invention applied to a construction having a typical free oiling mechanism for journal boxes, it is apparent that it may be used with journal boxes of various kinds.

The terms and expressions which we have employed are used as terms of description and not of limitation, and we have no intention, in the use of such terms and expressions, of excluding any equivalents of the features shown.

and described or portions thereof, but recognize that various modifications are possible within the scope of the invention claimed.

What we claim is:

- 5 1. In combination with a journal box, a journal in said box, a vertically disposed baffle member in the bottom of said box, and means including an element secured to said member and extending transversely thereof into engagement with the opposite walls of said box for holding said member rigidly in position, said member being constructed and arranged to limit upward movement of said box relative to said journal, and means on said box engageable by said member to limit upward movement thereof relative to said box.
- 10 2. In a journal box, a plurality of projections in said box, a baffle member positioned on one side of said projections, a yieldable element engaging the opposite side of said projections, and means securing said member and element in rigid relationship with said projections.
- 15 3. In a journal box having an enlarged portion at one end forming an oil reservoir, a journal in said box, oil conveying means on said journal, inward projections on said box adjacent the rear of said enlarged portion, removable means between said oil conveying means and the rear of said box separating said oil reservoir into a plurality of compartments, said removable means engaging said projections, and means engaging the opposite sides of said projections for securing said removable means in said box.
- 20 4. In a structure of the class described a journal box having an enlarged portion at one end forming an oil reservoir, a journal extending into said box, bearing means between said box and journal, oil conveying means operated by said journal for conveying oil from said reservoir to a point for delivery to said bearing means, removable baffle means beneath said journal extending into said reservoir adjacent said oil conveying means for deflecting oil splashed by said conveying means and returning it to said reservoir, and retaining means comprising a member cooperating with said baffle and with opposite walls of said journal box for rigidly securing said baffle means in said box.
- 25 5. In a structure of the class described a journal box having an enlarged portion at one end forming an oil reservoir, a journal extending into said box, bearing means between said box and

journal, oil conveying means operated by said journal for conveying oil from said reservoir to a point for delivery to said bearing means, removable baffle means adjacent the forward end of said journal between said oil conveying means and the rear of said enlarged portion and forming a pocket therewith for receiving foreign matter carried by the oil, and a member having a central portion engaging said baffle and end portions engaging portions of the walls of said journal box for rigidly securing said baffle in said box.

6. In a journal box having an oil reservoir in the bottom thereof, a journal in said box, a member adapted to be inserted in said box comprising a vertically disposed web portion extending into and above said reservoir, means extending laterally from said web portion adapted to underlie a portion of said journal box to limit upward movement of said member relative thereto, means engaging said web portion and portions of said journal box for rigidly securing said member in said box, and a projection offset from said web portion adapted to engage a journal in said box to limit upward movement of the latter relative to said journal.

7. In a journal box having an enlarged portion at one end and forming an oil reservoir, a journal in said box, means comprising an element intermittently contacting oil in said reservoir for raising oil therefrom to the top of the box to lubricate the journal, separable means extending into said reservoir for deflecting oil thrown rearwardly by said first mentioned means back into said reservoir, and means extending across the bottom of said box for securing said separable means therein.

8. In a journal box having an enlarged portion at one end forming an oil reservoir, a journal in said box, means comprising an element operated by said journal for distributing oil thereto, abutments on opposite sides of said box, a removable baffle member adjacent the end of said journal engaging the rear sides of said abutments and extending into said reservoir, said member projecting upwardly to said journal, means engaging the front sides of said abutments for securing said baffle to said box, and means on said baffle and box for limiting upward movement of said baffle relative to said box.

ALBERT O. BUCKLIUS.
THOMAS E. NEWBERRY.
